UNITED STATES PATENT OFFICE

90,581

DESIGN FOR A PORTABLE ELECTRIC
CUTTING MACHINE

Ivar Jeppsson, Chicago, Ill., assignor to Chicago
Flexible Shaft Company, Chicago, Ill., a cor-
poration of Illinois

Application May 27, 1933. Serial No. 48,221

Term of patent 14 years

To all whom it may concern:

Be it known that I, IVAR JEPSSON, a subject
of the King of Sweden, residing at Chicago, in the
county of Cook and State of Illinois, have in-
vented a new, original, and ornamental design for
a Portable Electric Cutting Machine, of which
the following is a specification, reference being
had to the accompanying drawing, forming part
thereof.

In the drawing—

Figure 1 is a perspective view of a portable
electric cutting machine showing my new design,
and

Figs 2 and 3 are side and top views thereof,
respectively.

My new design is characterized by an elongated
base having inclined sides, an upright housing
on the base shaped to substantially enclose the
disk cutter except for that portion exposed for
cutting, and a horizontally disposed handle form-
ing a motor casing attached at its front end to
the cutter housing and supported thereby.

I claim:

The ornamental design for a portable electric
cutting machine, substantially as shown and de-
scribed.

IVAR JEPSSON.
